UNITED STATES PATENT OFFICE.

THEODORE K. SAWYERS, OF MOORESVILLE, INDIANA, ASSIGNOR OF ONE-HALF TO CHARLES COOK, OF SAME PLACE.

ROAD SCRAPER AND LEVELER.

SPECIFICATION forming part of Letters Patent No. 300,287, dated June 10, 1884.

Application filed August 25, 1883. (No model.)

To all whom it may concern:

Be it known that I, THEODORE K. SAWYERS, of the town of Mooresville, county of Morgan, and State of Indiana, have invented 5 certain new and useful Improvements in Road Scrapers and Levelers, of which the following is a specification.

My said invention consists in an improved construction of the scraper-blade and other 10 parts of road scrapers and levelers, whereby said blade may be changed from a straight to a V-shaped blade, and other various adjustments may be easily and readily made, as will be hereinafter more particularly described.

15 Referring to the accompanying drawings, which are made a part hereof, and on which similar letters of reference indicate similar parts, Figure 1 is a top or plan view of my improved scraper; Fig. 2, an under side plan; 20 Fig. 3, a longitudinal vertical section of the same on the dotted line *z z* of Fig. 1; Fig. 4, a rear elevation; Fig. 5, a sectional view as seen when looking upwardly from the dotted line *y y* in Fig. 1; Fig. 6, a detail sectional view on the dotted line *x x* in Fig. 5; and Fig. 7, a sectional view, looking to the left from the dotted line *w w*.

In said drawings, the portions marked A represent the axle; B, the frame-work; C, the 30 pole; D, a timber on which the scraper-blade and double-trees are mounted; E, said scraper-blade; F, said double-trees; G G, levers by means of which the scraper-blade is vertically adjusted, and H the operator's seat.

35 The axle A supports the frame-work, and is provided with the usual wheels, A'.

The frame-work B is an ordinary square frame-work, and is mounted on the axle A, being bolted thereto by means of the bolts *a*. 40 It is provided at the rear end of each side piece with a suitable bearing, *b*, for the bell-crank lever *G*, and at the front ends with bearings for the levers G G.

The pole C is an ordinary draft-pole, the 45 rear end of which forms practically a middle piece to the frame-work B, it being bolted to the axle by one of the bolts *a*, and to the front and rear cross-pieces by means of bolts *b'* and *b*, respectively.

50 The timber D is hung directly under the pole C in clevis-like devices D' and D'', the

forward one of which is secured to the front cross-piece of the frame-work B by means of the bolts *b*, and is provided with a series of holes *d*, by means of which the forward end 55 of the timber may be bolted at any desired elevation. The rear clevis-like device is bolted to the rear end of the pole C by means of the bolt *e*, and prevents any lateral motion of the timber, at the same time serving as a guide 60 for its vertical adjustment. This is firmly held in position by the brace-rods *d' d'*, which run from its lower end on either side to the under side of the side pieces of the frame-work B, as shown. The forward clevis-like device, D', is 65 rigidly secured by means of the brace-rods *d'*, which run backward and outward from either side of the lower end of said device to the outer ends of the axle A, to the under side of 70 which they are bolted, directly under the side pieces of the frame-work B. As before mentioned, this timber is secured in position at its front end by means of a bolt passing through holes in the device D' and the end of said timber, and may be vertically adjusted in any position desired by changing said bolt from one 75 hole to another. Secured to the front end of this timber is a short cross-timber, D'', which is rigidly held in position by means of the brace-rods *d''*, which extend back from each 80 end thereof to the timber D, to the sides of which they are securely bolted. This cross-piece is provided with a row of holes, *d''*, (see Fig. 7,) its entire length, by means of which the double-trees may be adjusted to suit the 85 varying draft, as will be presently described.

The scraper-blade E is or may be of sheet metal, or wood with metal-cutting edges, as usual. It is jointed at its center, and is thus adapted to be converted into a V-shaped scraper when desired. It is preferably hinged on the angle-iron E', the vertical part of which serves as a hinge-pintle, and passes through the hinge parts *e* (which are slotted to permit the blade to fold into the V-shaped form) on the 95 center of the back side of the scraper-blade. Instead of this hinge arrangement, the two portions of the scraper may be connected by iron bars, either straight or of varying angles, according to the form of scraper desired, one 100 set of irons of course being replaced by another, as the form of the scraper is changed.

The other or longitudinal part of said angle-iron is flattened out and securely bolted to the under side of the timber D, directly under the axle A. The ends of the scraper are connected with the ends of the cross-timber D³, on which the double-trees are mounted, by means of the rods E² and E³, the rear ends of which are bent downwardly and extend down through the eyes e² and e³, respectively, thus firmly securing the scraper at both ends and in the middle directly to the draft devices of the machine.

The double-trees F are common double-trees, and are secured to the cross-piece D³ by means of a pivot-bolt, f, in the usual manner. When from any cause the draft is heavier on one side of the machine than the other, it can be readily equalized by withdrawing the pivot-bolt f and moving the double-trees to the proper side of the center the required distance, and until the hole in the center of said double-tree is directly over one of the holes d⁴ in the cross-piece, when the pivot-bolt is replaced and the double-trees thus secured in the required position to equalize the draft. By means of a series of holes, e⁴, in the front end of the rod E³ the angle at which the rear half of the scraper-blade is set with reference to the road may be varied, if desired, as will be readily understood, and as shown by the dotted lines in Fig. 2.

The levers G are mounted on suitable bearings, g, on the side pieces of the frame-work B in front of the axle A. They are provided with arms G', which extend out from the point where it is pivoted at nearly right angles with the main part of the lever. They are provided with ordinary spring-catches, g', which engage with the toothed sectors G³, and thus hold the lever in any desired position. These spring-catches are operated by means of the hand-levers G², to which they are connected by means of the rod g². When the scraper-blade is in the position shown, the lever on the right hand of the machine is used to adjust the forward end, and is connected thereto from the end of the arm G' by means of the rod G⁴. The left-hand lever is used to adjust the rear end of the scraper-blade. Its lower end is connected by the rod G⁵ to a bell-crank lever, G⁶, which is mounted on the bearing b on the rear end of the side pieces, B, and is connected to the scraper by means of a rod, G⁷.

When it is desired to set the scraper-blade at the opposite angle from that shown, it can be readily done by changing the places of the rods E² and E³, and also exchanging the connecting mechanism of the levers, when the left-hand lever will connect with the forward end, and the right-hand lever with the rear end, the bell-crank lever G⁶ being in such cases mounted on the bearing b on the right hand instead of on the left of the frame-work B, as will be readily understood.

When it is desired to change to a V-shaped scraper-blade, the long rod E³ is taken out and a short one, similar to E², is substituted, and

the mechanism of the lever on the left hand of the machine is dispensed with, and it is connected to the scraper, as is the right-hand lever, as shown.

The operation of my improved road scraper and leveler may be briefly recapitulated as follows: When it is desired to scrape the dirt from right to left, the scraper-blade is adjusted as shown, the holes e⁴ in the forward end of the rod E³ permitting the angle of the rear portion of the scraper-blade to be varied, if desired. When it is desired to scrape the dirt from left to right, the various connecting-rods are simply changed from one side to the other, as before described. When a V-shaped scraper-blade is desired, the long rod E³ is taken out, the several parts connecting the lever to the rear end of the blade are detached, the nuts which secure the hinge parts e are loosened, which permits them to slide upon the bolts by means of their slot-like holes, and thus the rear end of the scraper is permitted to swing forward to the desired position when connecting-rods similar to those used on the opposite side of the machine are substituted for those removed, and the blade is ready for work. The varying draft is equalized in all cases by adjusting the double-trees upon the cross-timber D, as before described.

Having thus fully described my said invention, what I claim as new, and desire to secure by Letters Patent, is—

1. In a road scraper or leveler, a scraper-blade having a joint in the center, by means of which it may be changed from a straight blade to a V-shaped blade, substantially as set forth.

2. In a road scraper or leveler, a scraper-blade having a hinge in the center thereof, the hinge parts being bolted to the back side of said scraper, and provided with longitudinal slots, by means of which they are permitted to slide upon the bolts after the nuts are loosened, and thus form an open joint, and permit said scraper-blade to be swung back into a V-shaped blade, substantially as set forth.

3. The combination, in a road scraper and leveler, of the frame, the timber D, the clevis-like devices D' and D'', whereby said timber is prevented from lateral motion, but is rendered vertically adjustable, and the scraper E, secured to said timber, substantially as set forth.

4. The combination, in a road scraper or leveler, of the timber D, to which the scraper-blade is secured, and the clevis-like device D'', in which the rear end of said timber is mounted, whereby it is rigidly secured from any lateral movement, and at the same time rendered susceptible of easy vertical adjustment, substantially as set forth.

5. The combination, in a road scraper and leveler, of the frame, the timber D, the scraper attached to said timber by iron E', and the clevis-like device D', in which the front end of said timber is mounted, provided with a

series of holes, d , by means of which the front end of said timber is secured at any desired elevation, substantially as set forth.

6. The combination, in a road scraper and 5 leveler, of the frame-work, the vertically-adjustable timber D, the scraper-blade secured thereto, the cross-timber D³, and the double-trees mounted thereon, said cross-timber being provided with a row of holes, d⁴, by means 10 of which said double-trees may be adjusted from side to side as the varying draft may require, substantially as set forth.

7. The combination, in a road scraper and 15 leveler, of the timber D, the cross-timber D³, provided with holes d⁴, the cleyis-like devices D' and D², for mounting said timber D, and the scraper-blade E, secured at its center to the under side of said timber, substantially as described, and for the purposes specified.

8. The combination, in a road scraper and 20 leveler, of the scraper-blade E, composed of two parts hinged together, the hinge-pintle E' being formed in the shape of an angle-iron, and its longitudinal portion being securely bolted to the timber D, said timber, the cross-timber D³, the stay-rods E² and E³, by means 25 of which the ends of the scraper are connected to the ends of said cross-timber, and the double-trees mounted thereon, substantially as described, and for the purposes specified. 30

In witness whereof I have hereunto set my hand and seal at Indianapolis, Indiana, this 11th day of August, A. D. 1883.
